UNITED STATES PATENT OFFICE

CARL GESKE, OF GRAND RAPIDS, MICHIGAN, ASSIGNOR TO WINTERS & CRAMPTON MANUFACTURING COMPANY, OF GRANDVILLE, MICHIGAN, A CORPORATION OF MICHIGAN

REFRIGERATOR LATCH

Application filed April 11, 1927. Serial No. 182,974.

This invention relates to latches and is more particularly concerned with latches which are to be used with refrigerators on the swinging doors thereof. In refrigerators, in many cases, the doors, which may be opened for access to the ice chamber and provision compartments of the refrigerator, are mounted to swing, some to the right and some to the left. It has been common practice heretofore to make two distinct types of latches for use on these differently swinging doors and the manufacturer was required to keep both types of latches in stock to take care of his requirements. This, together with the possibility that latches of one type might become inadvertently exhausted, and also from the reason that a considerable correspondence and resultant delay nearly always occurred when latches had to be supplied for replacement on refrigerators which had been sold and had left the factory, have made it very desirable that a single construction of latch be made which can be readily applied to either type of door, that is, whether swinging to the right or to the left.

This invention is directed to a latch of this character which may thus be readily applied to and used on a refrigerator door irrespective of the direction in which it is swung. The construction is very simple and effective and one which can be manufactured at low cost and in addition to the possibility of using the latch on doors swinging in either direction it also is equipped with a very simple and effective means for automatically holding the latch lever in retracted position when it has been released from its keeper when the door is to be opened. This eliminates the usual strain to which the fastenings securing the latch to a door are subjected as the end of the latch lever passes freely above the nose of the keeper and does not have to ride over a cam surface and there does not have to be a compression of the latch lever actuating spring as has been usual in spring actuated lever latches. The release of the latch lever after passing over the nose of the keeper is automatically effected as the door comes to

its closing position and all strain on the latch and its fastenings and on the door hinges and their fastenings are eliminated.

For an understanding of the construction which has been produced for the attainment of the above stated ends, as well as many others not particularly enumerated at this time, reference may be had to the following description taken in connection with the accompanying drawings, in which,

Fig. 1 is a fragmentary front elevation of a door and door casing, the latch attached to the door and the keeper attached to the casing being shown in elevation.

Fig. 2 is a horizontal section through the construction shown in Fig. 1.

Fig. 3 is an edge view of the construction shown in Fig. 1, the door being in partly open position and the latch lever held in retracted position and disengaged from the keeper.

Fig. 4 is a plan of the latch, the upper part of the casing being cut away and with the latch lever in normal central position.

Fig. 5 is a view similar to Fig. 4 but showing the latch lever moved to and held in retracted position.

Fig. 6 is an under plan view of the latch, the latch lever and bottom plate being removed.

Fig. 7 is a vertical section through the latch near one side of its casing or housing, and

Fig. 8 is a fragmentary plan view of the latch lever.

Like reference characters refer to like parts in the different figures of the drawings.

In the construction of the latch, a housing 1 of sheet metal is provided, it having the intermediate raised portion from which upwardly and downwardly extending ears or flanges 2 project, through which screws or similar fastenings pass into the door 3 to secure the latch permanently on the door. The raised portion of the casing has ends 4 and 5 in which openings 6 and 7 respectively are made for the passage of the latch lever. Ears 8 extend inwardly from each of the sides 4 and

5 into the openings 6 and 7 for the purpose of securing a bar of sheet metal 9 in place in the raised portion of the housing. This bar 9 extends across the housing and at each end is formed with an inwardly turned flange 10, the ears 8 being bent inwardly against the edges of said flanges. Bar 9 also between its ends is formed with two stop members 11 which are cut from the metal and turned inwardly at right angles, being spaced a short distance from each other.

10 A post 12 is secured permanently at one end to the bar 9 and extends inwardly, it being interiorly bored and threaded at its 15 inner end as best shown in Fig. 2. A spring is disposed on the post 12 being coiled as at 13 so as to pass around the post and having two ends 14 in the form of arms which extend substantially parallel to the length of the bar 9 and which are located one against the outer side of each of the stop members 11. These spring arms 14 are also bent inwardly as best shown in Fig. 2 so as to bear 20 against the upper side of the latch lever which is designed to have a double rocking mount on the post 12.

25 The latch lever 15 is formed at one end with a handle 16 and at its outer side a distance from its opposite end with an outwardly projecting lug 17. An opening 18 circular in cross section is made through the lever 15 between its ends and this opening is enlarged from the outer side of the lever 30 to the inner side as indicated at 19, whereby when the lever is placed over the post 12 it not only may have a rocking movement in a plane parallel to the plane of the face of 35 the door but also another rocking movement in a plane at right angles to the first plane. In the assembly of the lever on the post 12 as shown in Fig. 2 the coil 13 and the arms 14 of the spring are between the lever and the casing and the inwardly bent arms 14 come one against each side of the lug 17; and 40 the ends of said arms 14 bear against inclined surfaces 20 formed at the outer side and at each edge of the lever as best shown in Fig. 5. These spring arms hold the lever 45 in normal central neutral position and also have a tendency to rock the projecting end of the lever inwardly by reason of the pressure of the arms against the lever where the ends of said arms bear against the inclined surfaces 20.

50 The open inner side of the housing is closed by a base plate 21 which at one edge has a triangular-shaped member or shelf 22 bent back upon the base plate. The opposite edges 23 of the member 22 come together at the point or apex of the member as shown in Fig. 5. The plate is secured to the housing and also holds the latch lever on the post 12 by means of a 55 screw 24 which passes through an opening

in the base plate, threading into the end of the post 12 as fully shown in Fig. 2.

The keeper which is used with this latch is attached to the door casing 25 and comprises a base 26 through which screws may 70 pass to secure the same permanently to the door casing. From the base 26 a hook member 27 extends outwardly, it being of the form best shown in Fig. 3, having an outer cam surface 28 and an inner inclined surface 29, the two surfaces 28 and 29 meeting at the nose of the keeper hook 27. Integral with and projecting from the base 26 above the hook member 27 is a post 30 which at its outer portion is inclined upwardly and outwardly as indicated at 31.

75 When the door is in closed position, as shown in Fig. 1, the projecting end of the latch lever 15 is received in the keeper hook 27 and by reason of the pressure of the spring tending to maintain the lever in its intermediate normal position the lever is wedged against the inclined inner side 29 of the hook 27, thereby holding the door in 80 tightly closed position. When the door is 90 to be opened the handle 16 is grasped and the lever rocked in a plane parallel to the face of the door and against one of the arms 14 of the spring to the dotted line position 95 shown in Fig. 1. The lever rides over the member 22 until it passes an edge 23 thereof, whereupon the spring arm 14 which is engaged with the lever tends to rock the projecting end of the lever inwardly so that the lever may engage with the upper edge 23 of the member 22, as shown in Fig. 5. It is also apparent that the outward pull on the handle 16 in opening the door works with the spring in rocking the lever in a plane substantially at right angles to the plane of 100 the door so as to engage the lever against the upper edge 23 of the retaining member or half 22. The latch lever is released from the keeper and the door may be swung open and all the time that the door is open the 105 latch lever is held in its inoperative retracted position.

110 In closing the door the projecting end of the latch lever 15 comes against the part 31 whereupon the end of the latch lever is 115 dislodged from the retaining member or shelf 22 and the projecting end of the latch lever is released so that it may engage with the keeper hook. This occurs automatically as the door is closed. It is of course apparent that if for any reason the lever 15 does not engage with the retaining member or shelf 22 the door can be closed by applying sufficient force as the projecting end of the latch lever will then ride upon the cam 120 side 28 until it passes over the nose of the keeper as has been common in spring actuated latch levers used heretofore. And if, 125 through any circumstances, the lever should be turned in a direction opposite that which 130

it ought to be turned so that the projecting end of the lever is moved below normal central position and held by the under edge 23 of the retaining member or shelf 22, then when the door is closed the lever is dislodged from its engagement with the member 22 returning to central position and may then ride at its projecting end over the cam side 28 until it passes over the nose of the keeper and enters the recess of the keeper hook. This latch lever is shown as applied to a door hingedly mounted for swinging movement to the right but by merely reversing the position of the lever so that the upper and lower flanges 2 of the casings change position with each other this latch is then available for use on doors swinging to the left and the operation of the latch is the same as that described. Its automatic retention is retracted position is the same and the automatic release of the lever when the door is closed is the same as that previously described.

The construction of the latch is one of value, combining as it does in a latch having a construction adapted for application to either right or left swinging doors without change in the latch, the advantage that when applied to either kind of door the lever may be swung to retracted position, automatically held in such position all of the time that the door is open and automatically released to enter the keeper when the door is closed. The simplicity of construction of the latch, its economy in manufacture, and the simplicity and ease of its assembly are also further features of value in this construction. The invention is defined in the appended claims and is to be considered as comprehensive of all forms of structure coming within their scope.

I claim:

1. A latch construction comprising a housing, a bar secured in the housing at the outer part thereof, a pin extending inwardly from said bar, two spaced apart stop lugs on said bar located a short distance from the pin, a spring coiled around the pin and having two ends extending lengthwise of the bar to form spring arms, one bearing against the outer side of each lug, and a lever pivotally mounted on the pin, one of said arms bearing against each side of the lever to hold it in normal middle position, said lever being capable of rocking movement in either direction away from its normal middle position.

2. In a latch construction, a housing, a bar fixed in the outer portion of the housing, a pin attached to and extending inwardly from the bar, two spaced apart stop lugs extending inwardly from the bar a short distance from said pin, a spring coiled around said pin and having its ends extended into two arms located lengthwise of

the bar, each of said spring arms bearing with pressure against one of the lugs, a latch lever extending through the housing and pivotally mounted on the pin, and a lug extending from the outer side of the latch lever between the two spring arms, substantially as and for the purposes described.

3. In a construction of the class described, a housing, a pivot pin in the housing, a latch lever having an opening larger than the pin whereby the lever may have a rocking movement on the pin in two directions at an angle to each other, spring means coiled around the pin having ends extended into arms located in substantial alignment with the lever, two stationary stops secured to the housing located between said arms, means on the lever against opposite sides of which the two spring arms are located, a plate secured at the inner side of the housing, and means on the plate having two edges angularly disposed with respect to each other and with one of which the lever engages when rocked a predetermined distance away from its normal middle position, said lever being capable of rocking movements in both directions away from said middle position.

4. A reversible closure fastener for a hinged closure comprising a casing including a cover plate, a bolt pivoted in said casing for substantially equal angular movement above and below a horizontal or operative position, a spring secured to the bolt pivot and having free ends arranged to return said bolt to its horizontal position from either of its angular positions, and readily releasable means to hold said bolt in either of its angular positions.

In testimony whereof I affix my signature.

CARL GESKE.
